DISPLAY ICE CREAM ROADSTAND

Eugene Centrone, 101-07 Martense Ave., Corona, N.Y.

Filed Oct. 29, 1964, Ser. No. 82,382

Term of patent 14 years

(Cl. D13—1)

FIG. 2 is a top plan view thereof;

FIG. 3 is a front elevational view thereof;

FIG. 4 is a side elevational view thereof, and

FIG. 5 is a rear elevational view thereof.

The dotted lines shown in the several views are disclosed for illustrative purposes only.

The side of the roadstand disposed opposite the side shown but not shown is similar to the side shown.

I claim:

The ornamental design for a display ice cream roadstand, substantially as shown and described.
